UNITED STATES PATENT OFFICE

FRANK M. KINCAID, OF LIMA, OHIO, ASSIGNOR OF THREE-FOURTHS TO WILLIAM R. BASSICK, OF BRIDGEPORT, CONNECTICUT

VALVE SILENCER

Application filed April 23, 1928. Serial No. 272,054.

This invention relates to improvements in the poppet valve operating mechanisms of internal combustion engines, and has special reference to silencing and reducing the impact between the valve stem and its operating mechanism.

It is well-known that in a poppet valve type engine a clearance between the valve stem and tappet is necessary when the valve is closed, for the reason that heating and expansion of the valve stem and engine cylinder occur at different rates when in operation, so that with an unduly small initial clearance the valve may actually be held off its seat when it should be closed. The necessary clearance results in an impact or blow each time the valve is opened, and also when the valve returns to its seat because the closing velocity of the valve cannot be stopped completely due to the necessity of such a clearance.

It is therefore an object of this invention to provide an improved device for silencing or reducing the impact due to this clearance. In order to accomplish this result I have provided an improved operating mechanism adapted to provide a positive and timed opening and closing of the valve that is substantially noiseless in operation, and that provides a compensating feature automatically providing for normal wear and manually adjustable to insure initial and renewed proper timing of the valve.

It is also an object of this invention to relieve the valve stem proper of the direct load or pressure of the valve spring and to transfer the load to the push rod or valve tappet, thus taking up looseness of the operating parts and reducing the side thrust on the valve stem and guide.

It is another object of this invention to provide an improved and simplified device of the class described which can be manufactured at a reasonable cost and will be reliable in use.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmental vertical section through the cylinder of an engine showing one form of the valve operating mechanism of this invention partly in elevation.

Figure 2 is a section on the line II-II of Figure 1.

Figure 3 is a section, partly in elevation, of another embodiment of the invention.

Figure 4 is a section, partly in elevation, of a third embodiment of the invention.

Figure 5 is a section, partly in elevation, of a fourth embodiment of the invention.

Figure 6 is a section on the line VI-VI of Figure 5.

Figure 7 is a section, partly in elevation, of another modification.

Figure 8 is a section on the line VIII-VIII of Figure 7.

As shown on the drawings:

The parts of the engine chosen for illustration comprise the cylinder block including the wall 10 and piston 11 with a combustion chamber 12 indicated above the cylinder block, together with a valve seat 13 and intake or exhaust gas passage 14 formed in the cylinder block. The usual cam shaft 15 is shown with cams thereon which act against the bottom of a mushroom type of cam follower or tappet 16 sliding in a tappet guide bushing 17. The upper end of the tappet carries an adjustable set screw 18 with a lock nut 19 for adjusting the valve stem clearance.

A poppet valve of the usual form comprises a head portion 20 and a stem 21 sliding in a valve stem guide 22 inserted in a boss 23 formed in the cylinder block in alignment with the tappet and valve seat. The valve head is held against its seat by a valve spring 24, one end of which bears against the underside of the cylinder block around the boss 23, the other end of the spring resting in a spring retainer 25 which is held in position on a lower valve stem 26 by means of a lock 27. In an ordinary valve the lower stem 26 forms a continuation of the stem 21, whereas in the various embodiments of this invention shown on the drawings the lower stem 26 is a separate part.

In the embodiment of this invention shown

in Figure 1 the valve stem 21 and the lower stem 26 are both reduced in diameter for a short distance back from their adjacent ends to form pilots 28 and 29, which are continued for an equal distance as a shallow semi-circular section to engage two or three of the end coils of a closely wound spring 30, which acts to pull the upper valve stem downwardly thus seating the valve. The extreme ends 31 of the spring 30 are formed as inturned pins engaging in radial holes drilled into the valve stems.

In the operation of this form of valve structure it will be evident that the main valve spring 24 acts directly against the lower valve stem, which in turn presses on the tappet to cause it at all times to follow the cam. The inner spring 30 acts in tension to pull the valve stem 21 downwardly and is made lighter than the main valve spring, so that when the valve head seats the lower stem follows the cam and establishes the proper clearance between the two pilots 28 and 29, as indicated by the numeral 32.

The form of the invention shown in Figure 3 differs from Figure 1 only in the method of attaching the inner spring. The two valve stems 21 and 26 are formed with smaller pilot ends 33 and the inner spring 34 is slipped thereover and has two or three of its end coils welded to the pilots. This modification of the structure of Figure 1 permits the outside diameter of the spring 34 to be such that it will pass through the valve guide, thus simplifying the assembly of the complete valve in the cylinder block.

In Figure 4 no pilots are formed on the valve stems, a spring 35 being slipped over the adjacent ends which are separated by slightly yielding fiber washers 36, the spring ends being welded to their respective stem portions, as indicated by the numeral 37.

The modification of Figure 5 utilizes a stirrup or strap 38 enveloping collars 39 inserted in grooves in the upper and lower stems, respectively. A spring 40 is inserted between the lower end of the stirrup and the collar 39 on the lower stem 26, and a pilot 41 is formed on the upper end of the lower stem to receive a second spring 42. The second spring is intended to assist the maintenance of a clearance between the adjacent ends of the pilot 41 and the upper stem 21, while the spring 40 transmits the pressure of the main spring through the stirrup to the upper valve stem and head, this spring thus holding the valve head to its seat.

The modification of Figures 7 and 8 embodies a lost motion connection between the two valve stems, this connection comprising interengaging oppositely offset lugs 43 formed on the adjacent ends of the stems; the spring 35 of Figure 4 being used. As shown in Figure 7 the clearance has been taken up by an upward movement of the lower stem pre-

paratory to opening the valve. Normally the relatively heavy outer main spring would cause the clearance to be taken on the other sides of the lugs during the closed period of the valve.

It will thus be seen that I have provided an improved and simplified valve silencing device that materially reduces shock and wear in the valve mechanism.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. A valve mechanism of the class described comprising spaced upper and lower valve stems, a spring connecting said stems, said spring being initially tensioned, and a main valve spring engaging the lower valve stem adapted to cause the latter to closely follow the valve operating mechanism.

2. A poppet valve structure comprising a two-piece stem, a valve spring adapted to force the lower stem section downwardly, and a lighter spring joining the two stem sections and adapted to pull the upper stem section downwardly to cause seating of said valve.

3. A valve mechanism of the class described comprising an operating mechanism embodying a two-piece rod, one piece of which is adjacent the valve proper and the other movable relative thereto and follows the operating mechanism, a tensioned spring connecting the two pieces, and a main valve spring having its movable end engaged with the second rod piece.

4. A valve operating stem comprising spaced upper and lower segments, means yieldingly connecting said segments, and a valve spring operatively engaging the lower segment of said stem.

5. A valve actuating stem, a separate spaced extension thereof, means yieldingly urging said stem and extension together, and means acting on said extension adapted to seat said valve.

6. A valve operating stem comprising spaced upper and lower segments, a spring yieldingly connecting said segments, and a valve spring operatively engaging the lower segment of said stem.

7. A valve actuating stem, a separate spaced extension thereof, a spring yieldingly urging said stem and extension together, and means acting on said extension adapted to seat said valve.

8. A valve mechanism of the class described comprising an operating mechanism embodying a two-piece rod, one piece of which is adjacent the valve proper and the other movable relative thereto and follows

the operating mechanism, means yieldingly connecting the two pieces and a main valve spring having its movable end engaged with the second rod piece.

5 9. A valve operating mechanism comprising a two-piece valve stem, a tappet engaged by the lower piece of the valve stem, a spring connecting the lower piece to the upper piece of the stem, and a valve spring engaging 10 the lower piece of the stem and adapted to cause it to follow said tappet.

10 10. A two-piece valve stem, a spring connecting the two pieces of the stem, and a stronger valve spring engaging that portion 15 of the stem not associated with the valve whereby the latter portion is adapted to independently follow the valve operating mechanism.

11. A valve operating train comprising a 20 valve and a camshaft, a cam follower, means adapted to maintain said follower in contact with its cam on said cam shaft and yielding means connecting said last mentioned means to the valve.

25 12. A valve operating train comprising a valve and a camshaft, a cam follower, a spring adapted to maintain said follower in contact with its cam on the camshaft and a lighter spring opposed to said first mentioned spring and adapted to urge said valve towards said cam follower.

In testimony whereof I have hereunto subscribed my name at Chicago, Cook County, Illinois.
